UNITED STATES PATENT OFFICE.

HENRY H. LOGAN, OF CHICAGO, ILLINOIS.

BRAKE-OPERATING MECHANISM FOR ELECTRIC HOISTS AND THE LIKE

Application filed February 11, 1924. Serial No. 692,120.

To all whom it may concern:

Be it known that I, HENRY H. LOGAN,
a subject of the King of England, and a
resident of Chicago, county of Cook, State
5 of Illinois, have invented a new and use-
ful Improvement in Brake-Operating Mech-
anism for Electric Hoists and the like, of
which the following is a full, clear, and ex-
act description.
10 My invention relates to improvements in
brake operating mechanism for electric
hoists and the like, and more particularly to
a device for the purpose of regulating the
speed at which the brakes are applied, and
15 it consists in the combinations, constructions,
and arrangements herein described and
claimed.

An object of my invention is to provide a mechanism of the character described which when properly connected with a brake engine and a hoist control of the type shown in the patent to Lilly, No. 1,314,675, September 2, 1919, United States, will effect the immediate operation of the brakes when the hoist is in a position to bring the cage or skip to either of its limits of travel, or which will effect a gradual operation of the brake mechanism when the hoist is in such a position as to cause the cage or skip to be away from its limits of travel.

35 A further object of my invention is to provide a brake operating mechanism for electric hoists and the like which is entirely automatic in operation and therefore not dependent upon the actions of the engineer in any way.

A further object of my invention is to provide a brake operating mechanism for electric hoists and the like which may be used with any of the ordinary types of brake engines, either gravity operated or hydraulic.

45 A further object of my invention is to provide a device of the type described in which means is provided capable of manual adjustment for limiting the desired movement of the solenoid core upon the graduated cam member, whereby the speed of the operation of the brake mechanism may be further regulated.

50 Other objects and advantages will appear in the following specification, and the novel features of the invention will be particularly pointed out in the appended claims.

My invention is illustrated in the accompanying drawings, forming part of this application, in which

Figure 1 is a side elevation of an embodiment of my invention, and

Figure 2 is a side elevation of a modified form of a part of the mechanism illustrated in Figure 1.

In carrying out my invention, I make use of a cam dial 1, having a cam member 2 thereupon. The dial 1 is arranged to turn, and is synchronized with the hoist drum of a mine hoist, (not shown) in such a manner as to cause the cam 2 to engage with a roller 3 carried upon a pivotally supported rocker arm 4 when the skip or cage operated by the hoist is adjacent to either of its limits of travel.

The cam dial 1 is shown in the Lilly Patent No. 1,314,675 at 45 in Figure 1. It is connected by means of a chain 30^a to a gear 26 arranged to turn with the hoist drum 16 through a series of gears and shafts indicated at 26, 27, 28, 29^a and 30. The equivalent of the cam 2 in the Lilly patent is found in either of the two cams 77. 75 80

A rod 5 is pivotally connected at 6 with the rocker arm 4. A bell crank 7, pivotally mounted at 8, is provided with a weight 9 at the outermost end of the greater arm thereof. A rod 5 is pivotally connected at 10 with the bell crank 7, intermediate the weight 9 and the axis 8 of the crank arm. 85

A sliding stop member 11, mounted in a substantially horizontal plane, and arranged to slide upon a slideway 12 is pivotally connected at one end 13 thereof to the shorter arm of the bell crank 7 in such a manner as to cause a longitudinal movement of the stop member 11 when the cam 2 engages with the roller 3 of the rocker arm 4. The outermost end of the stop member 11 has a substantially inclined surface provided with a plurality of steps 14 each one receding further than the adjacent step, so that the step adjacent to the outermost end of the stop member 11 is closer to the slide-way 12 than that one adjacent to the body of the stop member 11, (see Figure 1).

The electrical equipment employed in my
brake operating mechanism, and which
forms a vital part of the brake engine op-
erating means, consists in a solenoid 15 con-
nected by means of lead wires 16 to an elec-
tric circuit in which a switch 17 and a cur-
rent source 18 form a part. 110

In the aforementioned Lilly Patent No. 1,314,675 the equivalent of the rocker arm 4 and the rod 5 may be found in the rocker

arm 79 and the rod 80. Particular attention is called to Figure 7 of the Lilly patent. The counterpart of the switch 17 in the Lilly patent is found in the switch illustrated in Figure 5 of which 52 and 53 are the contacts which when contacted with one another close a circuit to cause a weighted arm to fall. In my present invention, the switch 17 instead of closing upon the over-speeding of the hoist opens, thus permitting the solenoid to be de-energized.

A stationary supporting frame having members 19 has secured to it the solenoid 15 and is provided for slidably supporting a T-shaped solenoid core 20 in the manner shown in Figure 1. A movable core supporting frame having vertical supporting rods 21 is provided by means of which the core 20 is supported relative to the members 19. The upper ends of the rods 21 are secured together by a yoke 22 forming a part of the frame which is pivotally connected at 23 to a connecting rod 24. The rods 21 are slidably projected through the supporting members 19.

A stop screw 25 is disposed at the lowermost end of the core 20 and arranged for movement inwardly or out from the core 20, by rotation thereof, the screw 25 being provided with a hexagonal collar 26. A lock nut 27 provides ample means for locking the screw 25 against unintentional movement.

From the foregoing description of the various parts of the device, the operation thereof may be readily understood. Let us assume in the present installation of the device that the connecting rod 24 is connected directly with the valve of a brake engine of the hydraulic type, which is quite common in use, and that the cam dial 1 is properly synchronized with a hoist drum. If now the hoist drum is in such a position as to bring the cage or skip in the mine shaft at a point remote from the limits of travel, my improved brake operating mechanism will assume the position shown in Figure 1, i. e., the bell crank 7 will lie in such a position that the upper surface adjacent to the upper step 14 of the stop member 11 exactly underlies the stop screw 25. Let us assume that the switch 17 is opened. Current from the current source 18 will cease to flow through the solenoid, and the core 20 will drop, being limited in its downward movement by contact of the stop screw 25 with the stop member 11. As the core moves downwardly, the connecting rod 24 will move also and actuate the valve heretofore referred to, as forming a part of the hydraulic control of the brake engine. As a result, the brake engine will operate, but not suddenly, as movement of the valve is relatively slight.

If the switch 17 should open through over-speeding of the hoist drum when the cam member 2 is in engagement with the roller

3 of the rocker arm 4, or is partially in engagement therewith, then the bell crank 7 will be moved against the force of the weight 9 and one of the steps 14 of the stop member 11 will underlie the stop screw 25, depending entirely upon what portion of the cam 2 is in contact with the roller 3. Let us assume that the cam roller 3 is in engagement with the highest part of the cam 2. In this event, the outermost end 14 will underlie the stop screw 25 and permit the full downward movement of the core 20 so as to open the valve forming a part of the brake engine hydraulic system fully, thereby setting the brakes quickly. This is necessary, since if the cam 2 is in engagement with the roller 3, the hoist drum must be in a position which would bring the cage or skip adjacent to one of its limits of travel, either at the top or the bottom of the shaft.

It should be noted of course that my improved brake operating mechanism is not entirely limited in its application to hydraulic brake engines, and may be used with any type of gravity actuated brake engines which employ an adjustable cateract cylinder.

In Figure 2 I have shown a modified form of the stop member 11, in which the steps 14 are dispensed with, and a smooth inclined plane 29 is provided in their stead. The operation of this form of my invention is precisely the same as the preferred form, save for the fact that the degree to which the brake engine may be operated in units of time is more finely determined.

I claim:

1. An actuating mechanism for the control member of a brake engine comprising a solenoid, an electric circuit including a switch and said solenoid, whereby the opening of said switch may occasion the deenergization of said solenoid, a core in said solenoid arranged to drop when said solenoid is deenergized, a connecting rod associated with said core and arranged for connection with the control member of a brake engine, a stop engaging member carried by said core, a stop member having a substantially inclined surface arranged to receive the stop engaging member on said core when said core is dropped, and a cam operated means associated with said stop member for moving said stop member substantially at right angles with the direction of movement of said core, depending upon the instrumentality of said cam operated means, whereby the moment of travel of said core is determinable by the position of said stop member, and therefore the degree to which said brake engine control member is actuated is also determinable by the position of said stop member relative to said core.

2. An actuating mechanism for the control member of a brake engine comprising a solenoid, an electric circuit including a

switch and said solenoid, a core for said solenoid arranged to drop when said solenoid is deenergized, a connecting rod associated with said core and arranged for connection with the control member of a brake engine, an adjustable stop engaging member carried by said core, a stop member associated with said core and having a substantially inclined surface arranged to receive said adjustable member in engagement therewith when said core is dropped and to limit the downward movement of said core, a weighted member for normally maintaining said stop member in such a position as to permit minimum movement of said core when said solenoid is deenergized, as by operation of said switch, and cam operated means associated with said weighted member for elevating said weighted member, whereby said stop member may move and the lower portion of the inclined surface thereof may be in registration with the adjustable stop engaging member, thereby permitting a greater movement of said core downwardly, the degree to which said stop member is moved being directly determinable by the instrumentality of said cam actuated means.

3. An actuating mechanism for the control member of a brake engine comprising a solenoid, an electric circuit including a switch and said solenoid, a core for said solenoid arranged to drop when said solenoid is deenergized, an adjustable stop engaging member carried by said core, connecting means carried by said core and arranged for connection with the control member of a brake engine, a stop member disposed adjacent to said core and having a substantially inclined surface, a weighted member for maintaining said stop member in such a position as to permit minimum movement of said core downwardly, a connecting rod connected with said weighted member, a rocker

arm associated with said connecting rod at the opposite end thereof, and a cam member arranged to engage with said rocker arm to cause the elevation of said weighted member to a degree determinable by the instrumentality of said cam, whereby said stop member may move relative to said stop engaging member on said core and the lowermost parts of the substantially inclined surface thereof may lie in registration with said adjustable stop engaging member to permit greater movement of said core in the event of the opening of said switch.

4. An actuating mechanism for the control member of a brake engine comprising a solenoid, an electric circuit including a switch and said solenoid, a core for said solenoid arranged to drop when said solenoid is deenergized, an adjustable stop engaging member carried by said core, connecting means carried by said core and arranged for connection with the control member of a brake engine, a regulating stop member associated with said core and having a substantially inclined surface, a weighted member for maintaining said regulating stop member in such a position as to permit minimum movement of said core downwardly, a connecting rod connected with said weighted member, cam means arranged for synchronism with the hoist drum of a mine hoist and means arranged to cause the elevation of said weighted member to a degree determinable by the instrumentality of said cam, whereby said regulating stop member may move relative to said stop engaging member on said core and the lowermost parts of the substantially inclined surface thereof may lie in registration with said adjustable stop engaging member to permit greater movement of said core in the event of the opening of said switch.

HENRY H. LOGAN.
